UNITED STATES PATENT OFFICE.

THOMAS W. McNEILL AND IRA J. BABCOCK, OF CHICAGO, ILLINOIS.

SMOKE-INDICATOR.

1,012,403.

Specification of Letters Patent. Patented Dec. 19, 1911.

Application filed January 23, 1911. Serial No. 604,076.

To all whom it may concern:

Be it known that we, THOMAS W. McNEILL and IRA J. BABCOCK, citizens of the United States, all residing at Chicago, in the county of Cook and State of Illinois, have invented certain new and useful Improvements in Smoke-Indicators, of which the following is a specification.

Our invention relates to improvements in smoke indicators, and has among its general objects to provide an apparatus for association with a smoke ejection passage to enable its user to observe the relative transparency or opacity existent within said passage, such apparatus being simple in construction, easily adaptable for convenient location of its parts, and readily maintainable in efficient working condition.

In the drawings, wherein we have illustrated the embodiment of our invention, Figure 1 is a vertical cross section showing the application of a simple structure embodying the invention, as where the observation point is closely contiguous to the smoke flue; Fig. 2 indicates a form of structure employed where the observation point is remote from and non-aligning with the smoke flue from which the indication is taken; Fig. 3 is a detail of one of the parts of the apparatus; Fig. 4 is a horizontal section showing an application of the invention to a horizontal elbow in the smoke-ejection passage; and Figs. 5 and 6 are perspective details illustrating the construction of the device illustrated in Fig. 2.

Referring to the construction illustrated in Fig. 1, 10 indicates a fragment of a smoke flue—which may be specifically a smoke stack, breeching, or other duct through which the products of combustion from the fuel burner pass.

11 and 12 indicate apertures in the flue axially aligning in such relation that the escaping products of combustion must pass therebetween.

13 indicates a tube coaxial with the opening 11, and secured to flue 10, said tube inclosing a suitable source of light, herein shown as an electric incandescent lamp 14 located at a convenient distance, say about 12 inches from the opening 11 to the smoke flue.

The aperture 12 is exteriorly surrounded by a tube 15, attached to the flue 10, and extending to the observation point, said tube being closed at its extremity by a

screen 16 of ground glass or like translucent material, which is exteriorly surrounded by an open-ended hood 17. Thus, in general, it will be seen that light from the source of light 14 may pass through the light tube, crossing the smoke flue, and illuminating the screen 16, which is shaded by the hood 17 from the effect of extraneous light. Thus, an observer watching the spot of light on the screen or plate 16 may determine by the brilliancy of its illumination whether or not the smoke passage is clear, for obviously the passage of smoke through the flue 10 will obscure the light and decrease the illumination of the screen 16.

In providing a simple and efficient commercial construction, we mount the incandescent lamp 14 in a reflector 18, of suitable shape to direct the light rays in approximately parallel lines for concentration of the illumination. Any suitable source of light, producing substantially uniform illumination may, of course, be employed, with a reflector adapted to the light producer employed. The reflector member has an extension 19, pivoted as at 20, to a plate 21, carried by a thimble 22, partially telescoping in the tube 13. The thimble 22 has made therein a series of apertures 23 and the apertured zone of said thimble is overlaid by a sliding band damper 24, having therein similar apertures 25, so that by rotative adjustment of said band the open or effective area of said apertures 23 may be adjusted, thus to permit the entry of just enough air, under the inductive influence of the chimney draft, to keep the tube 13 always clear from accumulation of opaque matter which might tend to clog it and dim the reflector or lamp. The pivoting of the reflector member, however, enables the reflector easily to be swung to open position for cleansing, and also opening the end of the pipe so that it may readily be cleared of foreign substances that may have lodged therein notwithstanding the draft. A simple spring latch 26 is preferably provided normally to retain the reflector structure in closed position.

The ground glass screen is preferably mounted in a holder 30, provided with ears 31 pivoted to a pin 32, carried by a head plate 33, which is attached to the thimble 34, partly telescoping in tube 15, and provided with apertures 23', and a damper

structure 24' exactly as is the thimble 22, heretofore described. To the pivot pin 32 is also pivotally secured a hood plate 35, having an aperture 36 therein to expose the screen 16, said plate carrying the hood 17, secured to its exterior face. Thus, as seen in Fig. 5, the independent hinging of the plate carrier 30 and the hood carrier 35 enables all the parts of the device to be easily gotten at for cleaning, although the provision of the regulable draft apertures minimizes the necessity of such operation as heretofore described. The hinged parts are normally held in closed position by a latch 26', and all parts are permanently hinged together so that danger of breakage of glass is minimized.

The construction illustrated in Fig. 4 may be identical with that heretofore described, but it will be apparent from said Fig. 4, that in some instances the indicator tube members may be both on the same side of the smoke flue, although the indicator tubes must be so arranged that the products of combustion pass between the two members thereof in effecting escape.

In many installations it is highly desirable that the observations be taken at a station relatively remote from the point on the smoke flue where the condition is to be indicated, and in many instances it is impossible to employ straight piping to conduct the light to the point of observation. Obviously, the light conducting tube may take as many bends as desired or necessary if suitable mirrors or reflectors be provided for transmitting the light rays always in substantially parallelism with the axis of the tube, and therefore our invention contemplates the use of such mirrors as indicated in Fig. 2. It is important, however, that the mirrors be so constructed and arranged as to be susceptible of ready cleansing, so as to maintain the efficiency of the apparatus and also that provision be made against undue accumulation of foreign substances in proximity to such mirrors. Therefore, as indicated in Fig. 2, each mirror 40 is mounted in a frame 41, having ears 42 for pivotal attachment as at 43 to a suitable portion of an elbow structure 44, the thimble 45 nearest the smoke flue of each such elbow structure being provided with draft apertures 23" and a damper structure 24", substantially like the arrangement described with reference to the thimble 22. Thus in cleaning a mirror it is not detached from its support, and danger of breakage is practically eliminated.

Our invention has great utility in enabling the operator having charge of a fuel burner accurately to determine at all times the precise condition existing within the smoke eduction passage of his burner, as only by constant observation of such condi-

tion can he maintain the air supply for his fire at exactly the right proportion, avoiding loss of energy due to imperfect combustion, attendant upon deficiency of air supply, and equally avoiding the loss of energy resulting from the heating of an excessive air supply. Its merits in simplicity, practicability, ease of manipulation, and the like, are apparent.

While we have herein described in some detail a specific embodiment of our invention, it will be apparent to those skilled in the art that numerous changes in the details of construction might be made without departure from the spirit of our invention and within the scope of the appended claims.

What we claim is:

1. The combination with a smoke flue provided with openings between which the products of combustion pass, of tubes communicating with and open to the interior of the flue through said openings and axially alining with each other, lighting means for uniform illumination arranged within one of said tubes, a light receptive surface near the end of the other tube, and means for admitting air into each of said tubes between its ends.

2. In a smoke indicator, the combination with a flue having alining openings therein separated by the smoke path, two separate tubes in open communication with said openings arranged in axial alinement with their axes intersecting the axis of the smoke flue, a closure for the extremity of each of said tubes, lighting means for uniform illumination arranged within one of said tubes adjacent its end, said tube having between the source of light and the opening to the flue air entrance openings through which air may be entrained into the tube and into the smoke flue.

3. In a smoke indicator, the combination with a flue having alining openings therein separated by the smoke path, tubes communicating with said opening, a source of light associated with one of said tubes, a light-receptive surface associated with the other said tube, and means for admitting regulable quantities of air in one of said tubes.

4. The combination with a smoke flue, of a source of light, a tube opening into the flue and operatively associated with said source of light, a second tube opening to the flue in alinement with the first, said tube having openings for the introduction of air, and a light receptive surface operatively associated with said tubes beyond said openings.

5. In combination with a smoke flue, having alining openings in its walls, tubes communicating with said openings, a source of light and a light-receptive surface operatively associated with opposite extremities of said tubes, one of said tubes having open-

ings through its walls for admission of air, and damper means associated with said openings for regulating the effective area thereof.

6. In a smoke indicator, the combination with a smoke flue having alining openings in its walls, light directing tubes oppositely communicating with said openings, a source of light at the extremity of one of said tubes, and a light-reflector hinged to said tube, said tube having between the reflector and the smoke flue, openings for the admission of air.

7. An observation structure of a smoke indicator comprising a thimble for attachment to a tube, a plate, transversely connected therewith, a screen member pivoted to said plate, a second plate member pivoted to the first plate member, and a hood carried by the second plate member.

8. A light deflecting structure for a smoke indicator, comprising an elbow having two thimbles for connection with tubes, said thimbles being arranged with their axes at an angle to each other, a reflector hinged to said elbow for movement to open or close a wall of said elbow, said reflector

when closed standing in a plane at right angles to the line bisecting the angle between the axes of the thimble, and means for admitting regulable quantities of air into the interior of said structure.

9. In a smoke indicator having a tube through which light passes across a smoke flue, a lamp structure upon said tube for producing light comprising a reflector, a lamp mounted therein in proper adjustment, and means to mount said lamp and reflector in predetermined adjustment to said tube and to permit access to be had to said tube, lamp, and reflector without loosening of the parts or change of said adjustment, comprising a thimble having connection with the end of the tube, a plate carried by the end of the thimble, and positive hinge connections between said plate and the reflector.

In testimony whereof we hereunto set our hands.

THOMAS W. McNEILL.
IRA J. BABCOCK.
